Specification for Design.

Patented Nov. 18, 1919.

Application filed July 18, 1919. Serial No. 311,884. Term of patent 14 years.

To all whom it may concern:

Be it known that I, GEORGE C. GILL, a citizen of the United States of America, residing at Holyoke, in the county of Hampden and Commonwealth of Massachusetts, have invented a certain new, original, and ornamental Design for a Shield, of which the following is a specification, reference being had to the accompanying drawing, forming a part thereof.

The figure is a plan view of the shield showing my new design.

I claim:

The ornamental design for a shield, as shown.

GEORGE C. GILL.
